UNITED STATES PATENT OFFICE

ANDREW V. JORDAN, OF ASHER, OKLAHOMA

JACK

Application filed May 29, 1930. Serial No. 457,252.

The present invention relates to a jack and has for its prime object to provide a structure whereby the lifting element of the jack may be actuated upwardly by one stroke of a lever.

Another very important object of the invention resides in the provision of a jack of this nature which is exceedingly simple in its construction, inexpensive to manufacture, strong and durable, thoroughly efficient and reliable in use and operation, easy to manipulate, and otherwise well adapted to the purpose for which it is intended.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of a jack embodying the features of my invention,

Figure 2 is a sectional view therethrough taken horizontally on the line 2—2 of Figure 1,

Figure 3 is a vertical section through the jack,

Figure 4 is an end elevation thereof,

Figure 5 is a horizontal section taken substantially on the line 5—5 of Figure 3, and

Figure 6 is a perspective view of the catch.

Referring to the drawings in detail it will be seen that the numeral 5 denotes a base with a standard 6 rising therefrom and formed with a vertical bore 7 leading from the top end thereof and terminating in a vertical slot 8 in the lower portion of the standard. A shank 9 is slidable through the bore 7 and has a head 10 on the upper end thereof and its lower end is bifurcated and between the furcations 11 there is journaled a pulley 12. A lever L comprises a pair of side members 14 pivotally mounted intermediate their ends as at 15 on the sides of the standard 6 and adjacent ends project inwardly toward each other as at 17 and are engaged by suitable means 18 with a cable 19 which is trained under the pulley 12 and over a pulley 20 in a bracket 21 at the top of the standard and anchored as at 22 to a handle bar 23 fixed between sleeve segments

extensions 24 on the other ends of the arms 14.

It will therefore be seen that when the handle 23 is swung downwardly the cable is drawn over the pulley 20 and under the pulley 12 thereby raising the shank 9 and in order to hold the shank and its head 10 in a raised position I provide a catch 26 pivotally mounted as at 27 on the standard 6 alongside of the slot 8 for engagement with one of the side arms 14 and this catch is held in engaging position by means of a spring 28 which holds the lateral stop 29 in engagement with the standard.

It is thought that the construction, operation, utility and advantages of this invention will now be quite apparent to those skilled in this art without a more detailed description thereof.

The present embodiment of the invention has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A jack of the class described comprising a standard, a shank slidable longitudinally through the standard, a pulley on the inner end of the shank, a lever rockably mounted on the standard, a cable anchored to the lever at spaced points one to each side of the standard and trained under the pulley, a second pulley on the standard adjacent one end thereof over which said cable is trained.

2. A jack of the class described comprising a standard, a shank slidable longitudinally through the standard, a pulley on the inner end of the shank, a lever rockably mounted on the standard, a cable anchored to the lever at spaced points one to each side of the standard and trained under the pulley, a second pulley on the standard adjacent one end thereof over which said cable is trained.

one end thereof over which said cable is trained, said lever including a pair of arms one on each side of the standard and pivoted thereto.

- 5 3. A jack of the class described comprising a standard, a shank slideable longitudinally through the standard, a pulley on the inner end of the shank, a lever rockably mounted on the standard, a cable anchored to the lever
- 10 at spaced points one to each side of the standard and trained under the pulley, a second pulley on the standard adjacent one end thereof over which said cable is trained, said lever including a pair of arms one on each
- 15 side of the standard and pivoted thereto, adjacent ends of the arms projecting inwardly to which one end of the cable is anchored, a handle bar between the other ends of the arms and the other end of the cable being
- 20 anchored to the inner end of said bar.
4. A jack of the class described comprising a standard, a shank slideable longitudinally through the standard, a pulley on the inner end of the shank, a lever rockably
- 25 mounted on the standard, a cable anchored to the lever at spaced points one to each side of the standard and trained under the pulley, a second pulley on the standard adjacent one end thereof over which said cable is
- 30 trained, said lever including a pair of arms one on each side of the standard and pivoted thereto, adjacent ends of the arms projecting inwardly to which one end of the cable is anchored, a handle bar between the other
- 35 ends of the arms and the other end of the cable being anchored to the inner end of said bar, a catch pivotally mounted on the standard to engage one of the arms for holding the shank in a raised position.
- 40 5. A jack of the class described comprising a standard, a shank slideable longitudinally through the standard, a pulley on the inner end of the shank, a lever rockably mounted on the standard, a cable anchored to the lever
- 45 at spaced points one to each side of the standard and trained under the pulley a second pulley on the standard adjacent one end thereof over which said cable is trained, said lever including a pair of arms one on each
- 50 side of the standard and pivoted thereto, adjacent ends of the arms projecting inwardly to which one end of the cable is anchored, a handle bar between the other ends of the arms and the other end of the cable being
- 55 anchored to the inner end of said bar, a catch pivotally mounted on the standard to engage one of the arms for holding the shank in a raised position, the shank being bifurcated and said first pulley being journalled between the furcations thereof.

In testimony whereof I affix my signature.
ANDREW V. JORDAN.
